ATTORNEY.

UNITED STATES PATENT OFFICE.

AUGUSTUS BOWSER, OF FORT WAYNE, INDIANA.

CONTROLLING MECHANISM FOR LIQUID-DISPENSERS.

1,310,822.

Specification of Letters Patent.

Patented July 22, 1919.

Application filed April 28, 1919. Serial No. 293,280.

To all whom it may concern:

Be it known that I, AUGUSTUS BOWSER, a citizen of the United States of America, and resident of Fort Wayne, in the county of Allen and State of Indiana, have invented certain new and useful Improvements in Controlling Mechanism for Liquid-Dispensers, of which the following is a specification.

- 10 This invention relates to improvements in controlling mechanism for liquid dispensers, particularly of the type of that disclosed in my previous application for liquid dispensing apparatus filed October 4, 1918, 15 Sr. No. 256,795, and the object of the present invention is to provide means for operating simultaneously a valve that controls the passage of liquid through the feed pipe of the dispenser and an electric switch that 20 controls the means of supplying the liquid which passes through the feed-pipe, and also to construct the apparatus as to admit of adjustment of the several operating parts to insure proper simultaneous operation of 25 the valve and switch.

The objects of the invention are accomplished by the construction illustrated in the accompanying drawings in which:—

- 30 Figure 1 is a transverse vertical section of a part of a dispenser showing the valve and switch and also the adjustable arms respectively in operative relation therewith; Fig. 2 is a transverse section of Fig. 1 on the line $\alpha-\alpha$ of thereof;

- 35 Fig. 3 is a vertical elevation of Fig. 1 in a plane at right angles thereto and partly in section; and

- 40 Fig. 4 is a vertical elevation of the admission valve for controlling the passage of liquid through the feed-pipe.

Similar characters of reference indicate corresponding parts throughout the several views and referring now to the same:

- 1 is the supporting stand of a dispensing head through which a feed-pipe 2, drain-pipe 3 and electrical conduit 4 extend. The feed-pipe has connection at its lower end with a source of liquid under pressure and at its upper end with a suitable dispensing 45 receptacle and the feed-pipe is used for filling the receptacle; the drain-pipe 3 has connection with the lower end of the receptacle and its lower end has connection with the reservoir in which the liquid is stored; 50 and the conduit contains the electrical conductors 5 which lead to apparatus that gov-

erns the supply of liquid under pressure to the feed-pipe. The receptacle, reservoir and apparatus for supplying liquid to the feed-pipe are not herein shown, but are of the character disclosed in my previous application above referred to.

Interposed in the feed-pipe 2 is a T-connection 6 and also in the drain-pipe 3 is interposed a similar T-connection 7, the latter having projecting lugs 8, and a by-pass valve 9 has communication with each of the T-connections. The by-pass valve is normally held in closed position by means of a spring 10 contained therein. The feed-pipe 70 has also an interposed inlet valve 11 located below the T-connection 6 for controlling the flow of liquid through the feed-pipe into the dispensing receptacle.

In the lugs 8 on the T-connection 7 is mounted an oscillating shaft 12 that is held in adjusted positions vertically by jam-nuts 13, and on the extending lower end of the shaft 12 are adjustably mounted extending arms 14 and 15 respectively. The arm 14 is positioned so as to actuate an electrical switch 16 that is supported by the conduit 4 and wired in connection with the conductors 5, the arm 14 being adapted to move the push-button 17 of the switch inwardly 85 when the shaft 12 is oscillated and thus close the electrical circuit. The arm 15 is positioned so as to bear against the stem 18 of the inlet valve as it is moved inwardly and thus open the valve which permits the passage of liquid through the feed pipe into the dispensing receptacle, and also as the lever is moved the shaft 12 is correspondingly turned in the lugs which causes the arm 14 to close the switch 16.

The supporting stand 1 has a chambered protuberance 19 having a lid 20 for closing the same, and the latter has an outwardly extending flange 21 with an outer door 22 hinged thereto. A push button 23 is mounted with its stem 24 extending through the lid 20 so as to engage and actuate the arm 15 when pressure is applied to the push button. A movable pin 25 is also mounted in the lid 20 and so positioned as to engage the stem 26 of the by-pass valve 9 and actuate the valve when the door 22 is shut, there being a bearing bracket 27 on the inner face of the door that bears against the outer end of the pin and moves it inwardly against the valve stem so as to actuate the valve as the door is closed.

The valves 9 and 11 are each of the type shown in Fig. 4 of the drawings and are adapted to automatically close because of the action of the spring when pressure is removed from their stems. The switch 16 is of the push button type that normally remains open, and the circuit in which it is connected remains closed only during the time pressure is maintained against its stem 17.

In the operation of the invention the door 22 is opened thus exposing the push button 23 and releasing pressure against the stem 25 so that the by-pass valve is permitted to close which prevents liquid in the feed pipe from passing into the drain pipe. When the operator applies pressure to the push button 23 the arm 15 is moved inwardly against the valve stem 18 thus opening the inlet valve 11 which permits the passage of liquid in the feed pipe into the measuring receptacle, and also because of the connection of the arm 15 with the shaft 12, the latter is oscillated so that the arm 14 is moved against the stem 17 of the switch causing the latter to become closed. The movement of the liquid through the feed pipe is occasioned by force controlled by the closing of the switch. By adjusting the arms 14 and 15 upon the shaft 12 the closing of the switch and the opening of the inlet valve

11 may be made to occur simultaneously so that the liquid will be admitted through the valve at the same time pressure is applied to it to cause it to flow therethrough.

35

What I claim is:—

1. In apparatus of the class described having a feed pipe provided with an inlet valve and an electric switch adapted to close an electrical circuit that governs the supply of liquid to the feed pipe, two relatively adjustable arms pivotally supported, one of which is adapted to actuate the switch and the other being adapted to actuate the inlet valve, and being adapted to close the switch 40 and open the valve simultaneously, and means for operatively moving the arms.

2. In apparatus of the class described having an electric switch and an inlet valve; an oscillating shaft; two arms independently 50 and adjustably mounted upon the shaft, one of said arms being adapted to actuate the switch and the other the inlet valve; and means for operatively imparting movement to the arms.

In testimony whereof I affix my signature, in presence of two witnesses.

AUGUSTUS BOWSER.
